US00D899726S

(12) **United States Design Patent** (10) **Patent No.:** **US D899,726 S**
(45) **Date of Patent:** **** Oct. 27, 2020**

(54) **BUTTER STICK**

(71) Applicant: **LAND O'LAKES, INC.**, Arden Hills, MN (US)

(72) Inventors: **Joseph V. Burger**, Apple Valley, MN (US); **Jonathan Anderson**, Minneapolis, MN (US); **Sharon K. Cody**, Maple Grove, MN (US); **Lisa Ryan**, Lakeville, MN (US)

(73) Assignee: **LAND O'LAKES, INC.**, Arden Hills, MN (US)

(**) Term: **15 Years**

(21) Appl. No.: **29/712,907**

(22) Filed: **Nov. 12, 2019**

Related U.S. Application Data

(62) Division of application No. 29/660,645, filed on Aug. 22, 2018, now Pat. No. Des. 869,116.

(57) **CLAIM**

The ornamental design for a butter stick, as shown and described.

DESCRIPTION

FIG. 1 is an illustration of an isometric view of a first embodiment of a butter stick;

FIG. 2 is an illustration of a top view of the butter stick of FIG. 1 with the bottom view being a mirror image thereof; FIG. 3 is an illustration of a front view of the butter stick of FIG. 1, with the back view being a mirror image thereof; FIG. 4 is an illustration of a right side view of the butter stick of FIG. 1, with the left side view being a mirror image thereof;

FIG. 5 is an illustration of an isometric view of a second embodiment of a butter stick;

FIG. 6 is an illustration of a top view of the butter stick of FIG. 5 with the bottom view being a mirror image thereof; FIG. 7 is an illustration of a front view of the butter stick of FIG. 5, with the back view being a mirror image thereof; and,

FIG. 8 is an illustration of a right side view of the butter stick of FIG. 5, with the left side view being a mirror image thereof.

The evenly-spaced broken lines in FIGS. 1-8 illustrate portions of the butter stick that form no part of the claimed design. The dot-dash broken lines in FIGS. 1, 2, 5 and 6 illustrate the boundary of the claimed design which forms no part thereof. Any portions of the article between the break lines form no part of the claimed design.

1 Claim, 4 Drawing Sheets
